(57) **CLAIM**

The ornamental design for a light-emitting diode array, as shown and described.

DESCRIPTION

FIG. 1 is a perspective view of a light-emitting diode array showing our new design;

FIG. 2 is a front elevational view of the light-emitting diode array;

FIG. 3 is a rear elevational view of the light-emitting diode array;

FIG. 4 is a left side view of the light-emitting diode array;

FIG. 5 is a right side view of the light-emitting diode array;

FIG. 6 is a top plan view of the light-emitting diode array; and,

FIG. 7 is a bottom plan view of the light-emitting diode array. The broken line showing is for the purpose of illustrating environmental structure only and forms no part of the claimed design.
